ATTORNEYS.

UNITED STATES PATENT OFFICE

2,044,803

STUDIO LOUNGE

Ulysses Bruce McMurtry, Toronto, Ontario,
Canada

Application December 15, 1933, Serial No. 702,641

3 Claims.

(Cl. 5—44)

The present invention relates to studio lounges of the type which comprises two bed members, one of which slides horizontally over the other, when the lounge is in closed position.

5 A foldable "back" member is mounted on the lower bed and when said member is in lowered position it forms a support for a mattress, on top of the lower bed member. The back member also provides a support for a mattress when 10 the said member is in raised position. These features and their operation will be fully explained in the specification.

In the present device provision is made also for storage of bed clothing within the lower bed, 15 when both beds are in closed position. The upper bed may also be withdrawn from its closed position, and then forms a second bed of the same height, width and length as the lower bed. The nature of the structure used to accomplish 20 this end will be further explained in the specification.

A locking means whereby both bed members may be positively locked in closed position, is also provided in connection with the device in 25 hand, and explained below.

In the accompanying drawing forming part of the specification, I have illustrated one specific form of my invention in which:

Figure 1 is a plan view of a portion of the lower 30 bed with the back member in folded position thereon.

Figure 2 is an end view of the lower bed shown in Figure 1.

Figure 3 is a transverse section of the lower 35 bed.

Figure 4 is a plan view of one half of the lounge showing the upper bed in closed position on top of the lower bed, and the back member of the latter bed in raised position.

40 Figure 5 is a transverse section of the lounge in closed position, and taken on line 5—5 of Figure 4.

Figure 6 is a transverse section of the upper bed as taken on line 5—5 of Figure 4, the lower 45 bed being omitted therefrom.

Figure 7 is an enlarged side view of a locking means used for fastening the two beds together, when same are in closed position.

Figure 8 is a plan view of Figure 7.

50 In the drawing, the numeral 1 indicates a lower bed, which is substantially in the form of a box, with a lid or back-member, 2, which is hinged to the bed by means of the hinges 3, 3. Extending from the end wall 4 to the end wall 55 5 of the lower bed is a superimposed bar or

stringer 6, and it will be noted that the said end walls, when the lid 2 is in raised position, are of less vertical height than those of the upper bed 1, so that the latter may be slid over the top edges of the lower bed 1.

5 The stringer 6, when the beds are in closed position, as shown in Figure 5, forms a stop for the upper bed 1, and it will be noted that the locking means 8 shown in Figs. 7 and 8, is used to hold the front wall 9 of the upper bed in positively locked relation with the front wall 10 of the lower bed 1, but said beds may be easily unlocked and separated from each other by pressing the spring-held lever 11, shown in Figures 5 and 7.

15 The length of the box portion of the lower bed, which extends between the ends 4 and 5 thereof, is somewhat shorter than the space enclosed between the end walls 12 and 13 of the upper bed, so that the lower bed may be 20 slid within the said end walls of the upper bed, as can be seen from Figs. 4 and 5 of the drawing. However, on the outer surfaces of the ends 4, 5 of the lower bed two blocks 14, 14 are mounted which project outwardly in line with the 25 outer surfaces of the ends of the upper bed and they act as a support for the back-member 2 when same is in a lowered position, the front rail 35 of said back member resting on the front wall 10 of the lower bed 1.

30 The back-member 2 of the lower bed is composed of a bed-spring 15 and a pair of slotted bars 16, 16 are used on each of the ends of the lower bed member to provide holding means for the lid or back 2 when in raised position as 35 shown in Figs. 4 and 5 of the drawing. The said slotted bars 16, 16 are pivotally connected at 17, 17 to both ends of the lower bed on blocks 14, 14 respectively.

40 By means of projecting pins 18, 18 mounted in the ends of the lid or back-member 2 and operating in the slots 19, 19, the back-member 2 is held in raised position and yet may be closed down on top of the lower bed as illustrated in Fig. 2 of the drawing. When the back 2 is in lowered position it will be noted 45 that the opposed ends 20, 20 of same are in a position flush with the surfaces of the blocks 14, 14 and also flush with the ends 12 and 13 of the upper bed member so that both beds are of exactly the same length when they are separated from each other and the mattresses 21, 22 of both beds are of equal length.

45 The beds are also arranged to be of the same mattress-supporting width by maintaining the width of both beds of equal dimension as can be 50 55

seen from Figure 5 of the drawing in which the width between the outer faces 23, and 24 of the lower bed is the same as the width between the outer faces 25, 26 of the upper bed. In this way 5 both mattresses are of equal dimension and width and length and as has been described above, the height of both beds above the floor is the same when they are separated, due to the thickness of the back-member 2 when the lid is closed down 10 upon the box portion of the lower bed 1.

With reference to the upper bed, as has been described above, same comprises the opposed end walls 12, 13 and a front wall 9, and the top is formed by means of the bed-spring 27. These 15 features may be clearly seen in Figs. 4, 5 and 6 of the drawing.

The nature of the locking means 8 referred to above is well illustrated in Figs. 7 and 8 of the drawing in which a hinge 28 having a pintle 29 20 is mounted on the inner face of the front wall 9 of the upper bed. A bent plate 30 having an upstanding prong 31 is rigidly mounted on the horizontal portion of the hinge 28, and the spring 32 tends to hold the prong 31 when the beds are in 25 closed position as shown in Figure 5, in engaged position behind the plate 33 mounted on the front wall 10 of the lower bed 1. When the beds are separated the "offset" plate 34 acts as a stop against vertical rotary movement of the hinge 28 30 as is at once understood. When the upper bed is pushed into closed relation with the lower bed, the prong 31 automatically engages behind the plate 33, and when the beds are to be separated a slight manual movement of the end of the lever 11 35 at once disengages the prong 31, and permits removal of the upper bed.

The mattress 21 is lodged in the position shown in Fig. 5 when the beds are in closed position providing a back rest for the occupant of the lounge, 40 and the mattress 22 rests on top of the spring 27 forming part of the upper bed.

When it is desired to separate the beds and form two individual beds, or to form twin beds of equal height, width and length, the locking 45 device 8 is operated and the upper bed is drawn away from the lower bed 1. The mattress 21 is removed from the position shown in Fig. 5, the back member 2 is lowered on top of the lower bed 1 and said mattress 21 placed on top of the 50 back member as is at once understood. Thereafter the two beds so formed are either placed side by side, or used individually as separate beds. Both beds are provided with suitable castors on the bottom of each, so they may be readily moved 55 about on the floor. Any other equivalent locking means may be used in lieu of that shown and described herein, if desired, without affecting the operation of the beds.

It is seen that the handles 36 on each end of 60 the lower bed member 1 are adapted to act as

guides for the end walls of the upper bed 1, when the latter is being placed in closed relation to the lower bed, or removed therefrom.

It is evident the space contained between the 5 walls of the lower bed may be conveniently used for the storage of bed or other clothing, which is a very desirable feature of the invention.

From which it is seen that I have provided a very neat studio lounge, having the features necessary to provide twin beds of the same width, 10 length and height, and which may also be used as single beds if desired.

I claim:

1. In a box-type studio lounge, a lower bed comprising a box-like structure, an upper bed 15 adapted to slidably engage over a portion of the lower bed and locking means for holding the two beds in closed position, comprising a hinge mounted on the bottom of the upper bed, a bent plate rigidly mounted on said hinge, a downwardly 20 projecting plate mounted on the front of the lower bed, an upstanding prong on the end of the bent plate, an offset plate on the hinge providing a stop therefor and resilient means mounted on the upper bed and connected with said hinge for the 25 purpose of normally holding said prong in engagement with the said downwardly-projecting plate.

2. In a box-type studio lounge, a lower bed comprising a box-like structure, an upper bed 30 adapted to slidably engage over a portion of the lower bed, a longitudinal stringer mounted on the lower bed forming a stop for the upper bed, and locking means for holding the two beds in 35 closed position, comprising a hinge mounted on the bottom of the upper bed, a bent plate rigidly mounted on said hinge, a downwardly-projecting plate mounted on the front of the lower bed, an upstanding prong on the end of the bent plate, adapted to engage the downwardly-projecting 40 plate, an offset plate on the hinge providing a stop therefor, and resilient means mounted on the upper bed and connected with said hinge for the purpose of normally holding said prong in engagement with the said downwardly-projecting 45 plate.

3. In a box-type studio lounge, a lower bed comprising a box-like structure having a hinged back member mounted thereon forming a lid for the lower bed, an upper bed adapted to enclose 50 and cover a portion of the lower bed when the beds are in closed relation to each other, and a stop stringer mounted on the top of the lower bed, spaced a distance from the rear edge of same adapted to permit a cushion to be mounted on the 55 lower bed between the hinged back member and the inner edge of the upper bed, when said back member is in raised position.
